UNITED STATES PATENT OFFICE.

FRANCIS J. HINES, OF NEW YORK, N. Y.

ELECTRICAL RECEPTACLE.

Application filed September 16, 1922. Serial No. 588,607.

To all whom it may concern:

Be it known that I, FRANCIS J. HINES, a citizen of the United States of America, residing at New York city, Kings County,

5 New York, have invented a new and useful Electrical Receptacle, of which the following is a specification.

My invention relates particularly to what are commonly termed base receptacles.

10 The main object is to provide a construction in which several conductors may be connected to the same plug contacts without the necessity of soldering, splicing, or taping.

15 Another object is to construct such a device so that the connections may be readily made without the danger of short circuiting or grounding.

Another object is to so construct such a 20 device that a plurality of wires may be readily connected or disconnected at will.

In the accompanying drawings I have 25 illustrated one form of construction for accomplishing these objects. In its preferred

form the invention contemplates the use of a body portion with especially formed recesses and terminal members, and a cover member having passages for the usual knife blade or plug terminals.

30 Figure 1 is a face view of a base receptacle embodying the improvements of my invention.

Fig. 2 is a similar view with the cover member removed.

35 Fig. 3 is a sectional view of the body member and the attached terminals, the section being taken on the plane of the line 3-3 of Fig. 2.

Fig. 4 is a rear view of the cover member.

40 Fig. 5 is a sectional view of the same on the plane of the line 5-5 of Fig. 4.

Fig. 6 is a rear view of the device showing a number of conductors connected thereto.

45 Fig. 7 is a perspective view of one of the circuit terminals.

Fig. 8 is a perspective view of one of the plug terminals or sockets.

The body 10 and the cover 11 are 50 preferably formed of insulating material, the cover fitting into the outer edge of the body and being preferably surrounded by the flange 12. The body is provided with longitudinal channels 13 and 14 at opposite 55 sides and seats 15 and 16 for the cover. The cover may be held in place by a single

screw 17 and nut 18, the screw passing through the cover and the body, and the nut being located in the recess in the back of the body. Lugs 19 may be provided for 60 attachment to the usual metal box and for the attachment of the usual face plate (not shown.) These lugs may be secured to the body by screws 20. The feet 21 of these lugs may be positioned in notches 22 in the 65 ends of the body.

In the channels 13 and 14 are located terminal bus bars 23 which may be secured in place by screws 24. These terminal strips are provided with a plurality of binding screws 25-25 and passages 26 in line with passages 27 in the body of the receptacle. A number of pairs of conductors 28 and 29, 30 and 31 may thus be connected to the two opposite terminal bars so that a 75 plurality of circuits may be connected together through the medium of the terminal bars without the use of solder or twisting and taping the wires, and the consequent difficulty and danger of short circuiting, and 80 danger of accidental disconnection.

Each terminal bar has a foot 32 offset at one side and near one end for the connection of a socket member 33. These socket members may be of any suitable type 85 or design but are preferably designed so as to take what are commonly termed parallel or tandem plug blades and the cover plate is preferably provided with T-shaped 90 passages 34 to accommodate either arrangement of plug blades. The body of the receptacle is provided with recesses 35 adapted to accommodate the plug sockets and partitions 36 to insulate the plug sockets from the terminal bars of opposite polarity. 95

The bus bar 23 may be provided with a lug or flange 37 to assist in positioning the ends of the conductor wires.

The cover 11 may be provided with a raised insulating boss 38 to project through 100 the usual face plate opening.

By the construction as herein described it becomes a very simple matter to connect a plurality of wires where two or more cables come into the usual metal box, and I eliminate the possibility of a ground, a short circuit, a broken joint or splice, or damage of any kind to the wires.

I claim:

1. In a device of the character described, 110 an insulating body, a cover therefor having a single pair of passages, terminal bars ex-

tending along opposite sides of said body, a plurality of binding screws carried by each bar, said body having individual passages for wires leading to said binding screws and 5 plug sockets within said body connected respectively to said bars, and arranged in line with the openings in the cover to receive the blades of a plug.

2. In a device of the character described, 10 an insulating body having longitudinally extending channels in the face thereof and individual wire passages extending through the insulating body from the rear, terminal bars arranged in said channels, a plurality of binding screws to connect the bars with wires extending through said passages, a blade socket connected to each bar, insulating partitions between said sockets and the bars of opposite polarity, and a 15 cover plate having, in line with said sockets, passages for the blades of a plug.

3. In a device of the character described, 20 an insulating body having channels along opposite sides thereof, and insulating sup-

ports at the center and at the opposite ends 25 of said body between the channels, terminal bus bars located in said channels and insulated from each other, attaching lugs secured to said end supports, sockets connected to said bars between said supports, and 30 a cover plate having openings in line with said sockets and secured to said center support.

4. In a device of the character described, 35 an insulating body having parallel rows of wire passages extending to the back thereof, a cover therefor having a single pair of 40 passages, terminal bars extending over said rows of wire passages and having openings in register with the wire passages, a plurality of binding screws carried by each bar adjacent the wire openings, plug sockets connected respectively to said bars and located in recesses in said body, and arranged 45 in line with the passages in the cover, and attaching lugs secured to said body.

FRANCIS J. HINES
